UNITED STATES PATENT OFFICE.

ALBERT ENOCH COOPER, OF STAFFORD, ENGLAND, ASSIGNOR OF ONE-HALF TO
CHARLES JONES, OF LOWER BROUGHTON, SALFORD, MANCHESTER, ENGLAND.

NOTCHING OR LIKE PRESS.

Application filed March 20, 1922. Serial No. 545,230.

To all whom it may concern:

Be it known that I, ALBERT ENOCH COOPER, a subject of the King of Great Britain and Ireland, residing at Stafford, England, have invented new and useful Improvements in Notching or like Presses, of which the following is a specification.

This invention refers to presses or machines as used for cutting notches in the edges of sheet metal plates, rings or segments, and in particular the sheet metal stampings of laminated electrical machinery. Heretofore, said presses or machines have consisted of a perpendicular body part resting upon a table and at its upper end terminating in a single overhanging head part, through which works a plunger or slide carrying the upper notching punch or die, the lower notching punch or matrix being supported upon a foot or bed plate below said head part.

With such construction of press the cutting tool lies a considerable distance from the body part in order to allow for the notching of rings on their inner edges, with the width of the ring lying between the tool and the said body part. And in order to avoid flexure of the overhanging part during the punching operations the body part is made of relatively large section. Further, the fly wheel and driving gear are arranged above the press and do not allow of the rings being passed over the press to bring their inner edges between the notching tools. The said press also only allows of one plate being notched at a time.

One of the objects of this invention is to provide a press in which the body part can be of relatively small section whilst allowing of the width of the ring to be notched lying between the cutting tool and the said body part. A further object is to provide the body part with more than one overhanging head part and to arrange these at diametrically opposite points so that the forces acting upwardly on the tools will be balanced, or nearly so. A still further object is to provide a press in which more than one ring or segment can be notched at a time. According to the invention, the improved press comprises a perpendicular body part

with oppositely arranged overhanging head parts, and instead of being stationary, said body part is movable up and down with the head parts, the said body part being guided in a cylindrical guide or block fixed to the usual or other suitable table. The overhanging head parts lie relatively back to back and each is provided with a tool holder and tool, which coacts with the usual matrix carried by a relatively fixed flange or bed-plate. The means for operating the body part is preferably arranged below the table, and the power is applied centrally so that the pressure of the punches while acting on the rings or segments is equal.

To permit of the invention being more fully understood reference will now be made to the accompanying drawings, wherein:

Fig. 1 illustrates a side sectional elevation, and

Fig. 2 a plan of one example for the improved notching press.

Fig. 3 illustrates a sectional plan on line *a—a*.

Fig. 4 illustrates a further plan showing two segments in position for notching.

As shown, *a* is the body part of the press, the major part of which is cylindrical in cross section and is slidably mounted in a vertically disposed and open-ended cylinder *b*, this latter being provided with a flange *b*¹ by which it is supported on the table *c* of the machine. At its lower end the cylinder extends through an opening in the table and at its upper end the cylinder is slotted on two opposite sides.

At its upper end the body part *a* is formed or provided with two overhanging parts *a*¹, *a*² of equal size arranged at diametrically opposite points, each of said overhanging parts being parallel sided, and each projecting through and slidably fitting one of the slots or gaps in the upper end of the cylinder *b*. To each part *a*¹, *a*² is fitted a cap *a*³, by which the tool holder and tool *d* are carried. The complementary matrix *e* for each tool *d* is supported upon the flange *b*¹.

The cylinder *b* is flat-sided on its exterior, see Figure 3, and the top of the body part *a* is also flat-sided, and somewhat narrower than the cylinder, see Figure 2. Further,

the two overhanging head parts a^1 , a^2 , are narrower than the top of the body part a and thereby leave right-angled shoulders at a^4 , which in conjunction with metal strips f , bolted to the exterior of the cylinder b , serve to guide and steady the upper end of the body part a when moved up and down in the cylinder b . The table c is mounted upon the hollow stand or column b^2 .

10 The means for operating the said body part a consist of a rod g , passing down through the body part a which is formed with a conical through boring a^5 and a socket a^6 at its top end, the said rod having 15 ball-like part g^1 lying in said socket, and being free to oscillate therein. A plate h , with a like socket and through opening and secured by bolts or screwed studs to the body part a , serves to hold the rod and ball-like part in position, but with the ball-like part free to swivel in its sockets. Above the ball-like part the rod g is "squared" to receive 20 a "key." At its lower end the rod is screw-threaded and engages the screwed part i of a connecting rod head j , engaging the cranked part of the power shaft k , this latter being journaled in bearings carried by the column b^2 , and having a fly-wheel driving pulley k^1 .

30 With the machine in use, the rotary motion of the shaft k produces reciprocating up and down movement of the body part a and tools d , the degree of vertical movement being governed by the throw of the crank, 35 and the movement of the tools relatively to the matrices e being governed by the adjustment of the rod g relatively to the part i . The adjustment of the rod is effected by applying a "key" to its upper squared end and 40 rotating the rod to right or left.

The rings or segments requiring to be notched are placed upon the matrices e with one edge in the required position for the punch d to form the required notch. The 45 rings and segments will be fed to the press by the ordinary or other suitable spacing or dividing mechanism (not shown), each ring or segment being advanced the required distance for each notch.

50 As shown in full lines in Figure 3, the notches may be formed simultaneously on the inside edge of one ring and in the outside edge of another ring. Or as shown by chain lines in the same figure, a ring may be 55 placed around the press and its inner edges be notched whilst its width lies outside the tool instead of between the tool and the body part of the press, this being made possible by removing the driving gear from 60 above the press to a point below the press.

As shown in Figure 4, two segments may be notched simultaneously and one on the outside edge and the other on the inside edge.

The tools and matrices are adjustable towards and away from the body part a in the ordinary way, and the tool holders and matrix holders afford sufficient clearance between themselves and the cylinder b as to allow room for the ring feeding mechanism 70 to pass.

What I claim is:—

1. In a stamping or punching press, a body part having overhanging head parts at diametrically opposite points, a stationary cylindrical guide in which said body part moves vertically, a tool holder and tool carried by each overhanging part, a stationary support for said guide, matrices carried by said support one for each tool, and means for reciprocating said body part to operate the tools.

2. In a stamping or punching press, a body part having overhanging head parts at diametrically opposite points, a stationary cylindrical guide in which said body part moves vertically, a tool holder and tool carried by each overhanging part, a stationary support for said guide, matrices carried by said support one for each tool, and means below the said body part for reciprocating the same to operate the tools.

3. In a stamping or punching press, a body part having overhanging head parts at diametrically opposite points and each head part provided with a punch or tool, a table carrying complementary tools or matrices, one below each of the before-named tools, and means for causing the upper and lower tools to operate upon a stamping placed between them, as set forth.

4. In a stamping or punching press, a body part having overhanging head parts at diametrically opposite points, a stationary cylindrical guide in which said body part moves vertically, a tool holder and tool carried by each overhanging part, a stationary support for said guide and matrices carried by said support, a rod passing through the said head part, which is formed with a conical bore, a driving shaft, a crank on said shaft, and a connecting rod head engaging said crank at one part and the lower end of the rod at another part, and said rod at its upper end engaging the head part 115 through the medium of a universal connection, as set forth.

5. In a stamping or punching press, a body part having two overhanging head parts at diametrically opposite points, tool 120 holders and tools carried by said overhanging head parts, a stationary cylindrical guide in which said body part moves vertically the upper end of the guide having gaps through which the overhanging head parts 125 of the body part project and in which they slide, said guide and the upper end of the body part being flat sided on their exterior,

and the overhanging head parts being narrower than the said upper end of the body part and forming shoulders, metal strips applied to said guide and closely lying against the said shoulders of the body part, a table on which said guide is supported, and matrix holders and matrices supported by

said table, below the punching tools, and means for reciprocating the said body part to operate the tools, as set forth.

In testimony whereof I have signed my name to this specification.

10

ALBERT ENOCH COOPER
